UNITED STATES PATENT OFFICE.

RALPH J. SERPAS, OF KALAMAZOO, MICHIGAN.

BEATER ENGINE.

Application filed April 4, 1923. Serial No. 629,790.

To all whom it may concern:

Be it known that I, RALPH J. SERPAS, a citizen of the United States, residing at the city and county of Kalamazoo, State 5 of Michigan, have invented certain new and useful Improvements in Beater Engines, of which the following is a specification.

This invention relates to improvements in beater engines.

10 The main objects of this invention are:—

First, to provide an improved beater engine in which the beater roll is mounted upon fixed or non-adjustable bearings.

Second, to provide an improved beater 15 engine in which the bedplates are yieldably and adjustably supported so that they may be adjusted to the work required and so that the machine is not likely to become clogged, and the necessity of care in introducing the stock is eliminated.

Third, to provide an improved beater engine having these advantages which is very easily adjusted.

Objects pertaining to details and economies of construction and operation will definitely appear from the detailed description to follow.

I accomplish the objects of my invention by the devices and means described in the 30 following specification. The invention is clearly defined and pointed out in the claims.

A structure which is a preferred embodiment of my invention is clearly illustrated in the accompanying drawing forming a 35 part of this application, in which:

Fig. I is a plan view of a beater engine embodying the features of my invention.

Fig. II is a side elevation thereof.

Fig. III is a vertical longitudinal section.

40 Fig. IV is a vertical longitudinal section similar to that of Fig. III of a slightly modified form or embodiment of my invention.

In the drawing the sectional views are 45 taken looking in the direction of the little arrows at the ends of the section lines and similar reference numerals refer to similar parts in all of the views.

Referring to the drawing, the tank 1 is 50 provided with an inclined bottom 2 having a discharge spout 3 at its lower end controlled by the slide valve or gate 4. Beater rolls 5 and 6 are disposed in the ends of the tank, the ends of the tank being curved 55 so that they are concentric relative to the beater rolls, the beater roll 5 disposed at

the discharge end being considerably larger than the beater roll 6.

Between the beater rolls is a horizontal partition or midrib 7 inclined in a direction 60 opposite that of the inclination of the inclined bottom 2 of the tank. At its lower end the midrib 7 is provided with a discharge opening 8 controlled by the gate 9, the pivot rod 10 of this gate being extended through the wall of the tank and having an arm 11 constituting a handle. When this valve is lifted the flow of stock down the midrib assists in opening it and holding it open.

70 In the embodiment illustrated I provide two bedplates 12 for each beater roll, these bed plates being concave and seated in the curved end walls of the tank in complementary relation thereto. I have shown the beater bars conventionally as the mounting thereof forms no part of this invention.

The bedplates are adjustably and yieldably supported, being held yieldingly towards the beater rolls by the coiled springs 80 13 arranged between the bedplates and the cross bars 14. The bedplates are provided with threaded arms 15 having nuts 16 thereon disposed on the outer sides of the bars, thereby limiting the inward movement of 85 the bedplates under the action of the springs. These nuts are provided with bevelled pinions 17, there being several of the supporting arms for each bedplate.

To simultaneously adjust these nuts I 90 provide shafts 18 having pinions 19, the shafts being supported for rotative and axial movement in the bearings 20 on the bars 14 and being provided with hand wheels 21 by which they may be manipulated when 95 in engagement and rotated, thereby adjusting the bedplates.

Coiled springs 22 disposed between one of the bearings 20 and a collar 23 on the shaft hold the pinions 19 in disengaged position. 100

For convenience in manipulating the adjusting nuts of the lower bedplates the structure described is slightly modified, the nuts 24 corresponding to the nuts 16 being grooved to receive the yoke-like bracket 25 105 which carries the shaft 26 corresponding to the shaft 18, and carrying the pinions 27 meshing with the pinions 24, the pinions being in engagement at all times. Separate vertically disposed adjusting shafts 28 are 110 provided having pinions 29 adapted to be brought into mesh with the pinion 30 on the

end of the shaft 26. The pinion 29 is normally disengaged by the coiled springs 31.

The shafts 28 are provided with hand wheels 32. I thus provide a convenient 6 means for adjusting the lower bedplates, the adjusting means of which are normally below the level of the floor.

In the modification shown in Fig. IV the tank is provided with a top 33 and has a side 10 door 34 through which the stock may be introduced. The discharge gate 4 is operated with a rack and pinion mechanism but as the structural details of this mechanism form no part of this invention, they are not herein 15 described.

I have illustrated and described my improvements in an embodiment which I have found very practical. I have not attempted to illustrate certain modifications or adaptations 20 which I contemplate as I believe the disclosure made will enable those skilled in the art to which my invention relates to embody or adapt the same as may be desired.

Having thus described my invention what 25 I claim as new and desire to secure by Letters Patent is:

1. In a beater engine, the combination with a tank having a bottom inclined toward one end with a valved discharge at its 30 lower end, beater rolls mounted on relatively fixed bearings at the ends of the tank, the end walls of the tank being vertically curved and overhanging said beater rolls, a horizontal midrib disposed between said beater rolls in an oppositely inclined relation to the bottom of the tank and having a valved discharge at its lower end, concave bedplates disposed in complemental relation to the curved end walls of said tank, there being 35 a pair of bedplates coacting with each beater roll, one being positioned below and the other above the same, means for supporting said bedplates for radial adjustment relative to the beater rolls comprising supporting bars, threaded arms on said bedplates disposed through said bars, coiled springs arranged on said arms between said bedplates and supporting bars, nuts threaded upon said arms at the outer sides of said supporting bars, said nuts being provided with bevelled pinions, and adjusting shafts mounted transversely of said arms and provided with bevelled pinions coacting with the pinions on said nuts.

2. In a beater engine, the combination with a tank having a bottom inclined toward one end with a valved discharge at its lower end, beater rolls mounted on relatively fixed bearings at the ends of the tank, the 60 end walls of the tank being vertically curved and overhanging said beater rolls, a horizontal midrib disposed between said beater rolls in an oppositely inclined relation to the bottom of the tank and having a valved discharge at its lower end, concave

bedplates disposed in complemental relation to the curved walls of said tank, there being a pair of bedplates coacting with each beater roll, one being positioned below and the other above the same, and means for supporting said bedplates for radial adjustment relative to the beater rolls. 70

3. In a beater engine, the combination with a tank having a bottom inclined toward one end with a valved discharge at its 75 lower end, beater rolls mounted on relatively fixed bearings at the ends of the tank, the end walls of the tank being vertically curved and overhanging said beater rolls, a horizontal midrib disposed between said beater rolls in an oppositely inclined relation to the bottom of the tank and having a valved discharge at its lower end, concave bedplates disposed in complemental relation to the curved end walls of said tank, means for supporting said bedplates for radial adjustment relative to the beater rolls comprising supporting bars, threaded arms on said bedplates disposed through said bars, coiled springs arranged on said arms between said bedplates and supporting bars, nuts threaded upon said arms at the outer sides of said supporting bars, said nuts being provided with bevelled pinions, and adjusting shafts 85 mounted transversely of said arms and provided with bevelled pinions coacting with the pinions on said nuts. 90

4. In a beater engine, the combination with a tank having a bottom inclined toward one end with a valved discharge at its lower 100 end, beater rolls mounted on relatively fixed bearings at the ends of the tank, the end walls of the tank being vertically curved and overhanging said beater rolls, a horizontal midrib disposed between said beater rolls in an oppositely inclined relation to the bottom of the tank and having a valved discharge at its lower end, concave bedplates disposed in complemental relation to the curved end walls of the said tank, and means for supporting said bedplates for radial adjustment relative to the beater rolls. 105

5. In a beater engine, the combination with a tank, beater rolls mounted at the ends of the tank, a horizontal midrib disposed between said beater rolls, bedplates disposed in coacting relation to said beater rolls, there being a pair of bedplates coacting with each beater roll, one being positioned below and the other above the same, means for supporting said bedplates for adjustment relative to the beater rolls comprising supporting bars, threaded arms on said bedplates disposed through said bars, coiled springs arranged on said arms between said bedplates and supporting bars, nuts threaded upon said arms at the outer sides of said supporting bars, said nuts being provided with bevelled pinions, and adjusting shafts 115 mounted transversely of said arms and pro- 120

125

vided with bevelled pinions coacting with the pinions on said nuts.

6. In a beater engine, the combination with a tank, beater rolls mounted at the ends of the tank, a horizontal midrib disposed between said beater rolls, bedplates disposed in coacting relation to said beater rolls, there being a pair of bedplates coacting with each beater roll, one being positioned below and the other above the same, and means for supporting said bedplates for adjustment relative to the beater rolls.

7. In a beater engine, the combination with a tank, beater rolls mounted at the ends of the tank, a horizontal midrib disposed between said beater rolls, bedplates disposed in coacting relation to said beater rolls, there being a pair of bedplates coacting with each beater roll, one being positioned below and the other above the same, means for supporting said bedplates for adjustment relative to the beater rolls comprising threaded arms on said bed plates, pinions having threaded engagement with said arms, and shafts provided with pinions coacting with said pinions on said arms.

8. In a beater engine, the combination with a tank, a beater roll, a concave bed plate operatively associated therewith, means for supporting said bedplate for radial adjustment relative to the beater roll comprising a supporting bar, threaded arms on said bedplate disposed through said bar, coiled springs arranged on said arms between said bedplate and supporting bar, nuts threaded upon said arms at the outer side of said supporting bar, said nuts being provided with bevelled pinions, an adjusting shaft mounted on said supporting bar for axial and rotative movement and provided with bevelled pinions adapted to be engaged with the pinions on said nuts by axial movement of the shaft, whereby the several adjusting nuts may be simultaneously adjusted, and a

spring for holding said shaft with its said pinions normally in disengaged position.

9. In a beater engine, the combination with a tank, a beater roll, a concave bedplate operatively associated therewith, means for supporting said bedplate for radial adjustment relative to the beater roll comprising a supporting bar, arms on said bedplate disposed through said bar, coiled springs arranged on said arms between said bedplate and supporting bar, pinions having threaded engagement with said arms, and an adjusting shaft provided with pinions coacting with the pinions on said arms.

10. In a beater engine, the combination with a tank, a beater roll, a bedplate operatively associated with said beater roll, means for adjustably and yieldingly supporting said bedplate relative to the beater roll comprising a supporting bar, threaded arms on said bedplate disposed through said bar, coiled springs arranged on said arms between said bedplate and supporting bars, nuts threaded upon said arms at the outer sides of said supporting bar, said nuts being provided with bevelled pinions, and an adjusting shaft mounted transversely of said arms and provided with bevelled pinions coacting with the pinions on said nuts.

11. In a beater engine, the combination with a tank, a beater roll, a concave bedplate operatively associated with said beater roll, means for adjustably and yieldingly supporting said bedplate relative to the beater roll comprising arms on said bedplate, springs for yieldingly supporting said bedplate, pinions having thread engagement with said arms, and an adjusting shaft provided with pinions coacting with the pinions on said arms.

In witness whereof, I have hereunto set my hand.

RALPH J. SERPAS [L. s.]
